2 SHEETS—SHEET 2.

UNITED STATES PATENT OFFICE.

EDWARD H. ELLISON, OF JAMESTOWN, NEW YORK.

PEDAL ACCELERATOR FOR AUTOMOBILES.

1,408,572.

Specification of Letters Patent.

Patented Mar. 7, 1922.

Application filed July 23, 1920. Serial No. 398,382.

To all whom it may concern:

Be it known that I, EDWARD H. ELLISON, a citizen of the United States, residing at the city of Jamestown, in the county of 5 Chautauqua and State of New York, have invented certain new and useful Improvements in Pedal Accelerators for Automobiles, of which the following, taken in connection with the accompanying drawings, is 10 a specification.

The invention relates to foot or pedal accelerators as especially adapted for application to internal combustion engines in automobiles of the Ford type, the present 15 invention being an improvement upon the accelerator construction shown in my Letters Patent, No. 1,361,374, dated Dec. 7, 1920; and the object of this improvement is, first, to provide a two-piece pedal or foot actuating 20 lever with an adjustable joint between the parts thereof which will give positive holding power to the foot contacting portion of the pedal with a wide area as to adjustment by means of a fan-shaped corrugated or 25 toothed portion which intermeshes with similar corrugations or teeth on the opposite portion, one of said portions being slotted to receive one of the screw bolts so that when bolted firmly in the adjusted position, 30 the joint is absolutely rigid; and second, to provide certain simplifications of the arm, link and bell crank connections which strengthen the construction, and at the same time render the action more accurate and 35 positive; and the invention consists in the novel features and combinations hereinafter set forth and claimed.

In the drawings, Figure 1 is a perspective view of the accelerator mechanism attached 40 to the engine showing the improved construction and arrangement of the same. Figures 2 and 2^a show a detail perspective view and elevation of an adjustable rod end mechanism. Fig. 3 is a perspective view of 45 the two-piece pedal showing the corrugated joint between the two parts thereof, one of the parts being broken away at said joint to better reveal the same; and Fig. 4 is a sectional view of the corrugated portions 50 of the joint with the main portions of both the parts broken away. Figs. 5 and 5^a show side and edgewise elevations of the bracket plate for the bell crank lever. Fig. 6 is a top plan view of the accelerator mechanism 55 attached to the engine, a portion of the engine being broken away to show the connect-

ing rod to the carburetor actuating lever, and also from the bell crank lever to the steering column. Figs. 7 and 7^a show detail side elevations of the joint between the link 60 connection and the carburetor actuating lever. Figs. 8 and 9 show different positions of the end joint in the bell crank end of the link to the pedal actuating arm; and Fig. 10 is a side elevation of said link turned 65 oppositely to the manner in which it is shown in Fig. 1 to show the adaptation of said link to engines of different heights.

Like characters of reference refer to corresponding parts in the several views.

The numeral 15 designates the two-piece pedal, the two parts being designated by the numerals 16 and 17 which are provided with the corrugated lap joint 18, the adjacent faces of the interlapping parts being similarly corrugated.

The end portion 19 of one of the parts is made fan-shaped so that the corrugated side of the end part 20 of part 17 fits in said corrugations of the fan-shaped part 19 at different angles of adjustment, two screws 21 and 22 being provided to attach the two parts, the fan-shaped portion 19 having a slot 23 to adjustably receive the screw bolt 22 thereby making a rigid joint having a wide 85 adjustment which can be quickly and easily attained by loosening the bolts sufficiently to turn the toothed or corrugated portions upon one another to the desired adjustment. This arrangement permits the quick removal 90 of the screw at said lap joint to thereby disconnect the portion 16 of the pedal 15 from the portion 17 to allow the removal of the floor board 24 without disturbing the adjustment of any of the other parts of the accelerator mechanism.

The part 16 has the knurled or rubber surfaced foot rest 25 which is pivotally attached at 26 near the end of said board 16, the face of the foot rest 25 being a 100 segment of a circle which is centered by the pivot pin 26 so that said foot rest 25 will turn pivotally under foot pressure without slipping and the loss of control by the enforced movement of the foot upon 105 said foot rest. The hinged foot rest 25 has the two stops 27 and 28 therefor on the part 16, said foot rest 25 being balanced to normally fall back upon the stop 28 by gravity so that it is always in readiness for 110 instant use, the foot pressing upon said foot rest 25 radially at different angles

according to the position of the chauffeur in relation to the same. This arrangement permits the user to move the lever 15 with absolute exactness of foot pressure upon the same in accelerating the engine. If the foot rest 25 centers radially upon the pin 26 and the periphery of the foot rest 25 curves in exact radial line, the foot of the user will obtain a purchase upon said 10 foot rest that it would not otherwise find if said outer periphery were at any other curve. In this perfect circumference, the foot rest 25 moves from the normal non-accelerating position to the full limit of acceleration of the engine with a graduated pressure exactly in accord with the user's intention.

The lever part 17 is connected to the shaft 29, which shaft is rotatably mounted 20 in the bracket 30. The bracket 30 is designed to fit onto and be adjusted by the spaced bolts 31 upon the engine head plate 32, which is common to all Ford engines. The bolts 31 are always in the same position so that little skill is required in attaching this part of the accelerator mechanism to the engine since it cannot be installed otherwise than correctly in place upon said bolts 31. The part 17 of the pedal 15 is 25 provided with the stops 33 and 34 which limit the movement of the pedal 15 in both directions, that is, to the complete closure and full actuation of the carburetor and relieves the carburetor and accelerator mechanism of all strain.

The shaft 29 is extended sufficiently to one side for the attachment of the downwardly extending arm 35. A link 36, preferably flat, is attached to the lower end of 40 the arm 35 at one end and to the bell crank lever 37 at the other. The attachment of the arm 35 to the link 36 renders the arm and link adaptable to different heights of engines by turning the end 42 in a return bend and 45 providing a hole through each of the parts so that said link 36 is reversible, being shown in Fig. 1 one side up and in Fig. 10 with the other side up. The lower end of the arm 35 is preferably attached with a 50 coil take-up spring 43 and cotter pin for quick and noiseless attachment, the spring 43 acting as a constant take-up, that is, holding the arm 35 and link 36 under tension without rattle, yet permitting the free 55 action of the same.

The bell crank lever 37 is pivotally attached to the bracket plate 38, which bracket plate 38 is attached to the engine 32 by means of the screw bolt 39, the two screw 60 bolts 39 and 40 being regular attaching bolts for the engine parts in order to hold the bracket piece 38 against turning. The end 41 is notched or curved to fit over the bolt head 40 as shown at 41. This gauges 65 the exact position of the plate 38, the bolt

39 being sufficient to hold said plate firmly attached to the engine. The link 36 is attached to the bell crank lever 37 by means of a winged nut or pin 44. The hole 45 in the end of the link 36 is made the same 70 shape as said winged nut or pin so that said link may be slipped over the same and then turned into the locking position as shown in Figs. 8 and 9, which brings it into alignment with the arm 35 for attachment thereto, thereby making a quick and firm locking attachment for said link 36 to the bell crank lever 37.

The opposite arm of the bell crank lever 37 is pivotally connected to the carburetor 80 actuating arm or lever 46 by means of the link 47, which link or rod 47 is turned at right angles and extends down through a hole in the end of the arm of the bell crank lever 37 and is turned to one side slightly 85 into alignment with the carburetor actuating lever 46 and adjustably extends its threaded end through the threaded sleeve of the pin 48 so that said link 47 can be adjusted to 90 actuate the carburetor 49 as desired.

A link 50 encircles the angular end of the link 47 where it extends through the arm of the bell crank lever 37 in order to attain a strong and economical pivotal attachment for the end of the link 50, the 95 other end extending through a sleeve 51 which is pivotally attached to an arm 52 on the steering column operating or throttle rod 53. The end of the link 50, after passing through the hinging sleeve 51, is 100 threaded and has the U-shaped threaded nut 54 thereon and the cotter pin 55, as shown in detail in Fig. 2, thereby giving a quick and accurate adjustment for the length of the link rod 50.

In order to attain a constant tension on the parts and particularly on the pedal 15, an arm 56 is attached on the shaft 29 to be actuated thereby, and has the coil tension spring 57 adjustably attached in one of the 110 holes 58 according to the leverage and consequent strength of tension desired, the other end being attached through the hole 59 in the bracket plate 38 immediately beneath the end portion of the arm 56. This gives a 115 constant spring tension upon all the parts, ensuring the accurate actuation of the carburetor actuating lever 46. The spring 57 serves to raise the lever 15 and also brings the accelerator mechanism back to normal 120 idling position whenever foot pressure is removed from the pedal, the spring 57 holding against the stop 34 in attaining the tension on all of the usual parts of the accelerator mechanism, preventing all rattling when in 125 said normal idling position. The connection to the operating rod 53 of the steering column permits the operation of the hand lever on the steering column so that it is not in any way interfered with, retaining any po- 130

sition as adjusted by the driver of the vehicle.

The opening through the engine is narrow and in this confined space there is room for 5 only a single rod 47 to work freely without hindrance from the parts of the engine as the bell crank 37 actuates the carbureter arm 46. The single rod 47 is plain and smooth without any sleeves or other parts thereon 10 and passes through the engine without catching on any of its parts. The link rod 50 as well as rod 47 has the adjustably threaded ends 54 and 48 so that the length of the two rods 50 and 47 may be adjusted as desired 15 so as to open or close the carbureter 49 and obtain the desired amount of gas.

What is claimed is:

1. In an accelerator construction for motor vehicles, a rock shaft, a pedal connected thereto, an arm also connected to the rock shaft, a throttle element, and means connecting the arm to the throttle element and including a reversible member having spaced parts each of which is formed for selective attachment to the arm so as to accommodate engines of varying heights.

2. In an accelerator construction for motor vehicles, a rock shaft, a pedal connected thereto, an arm also connected to the rock shaft, a throttle element, and means connecting the arm to the throttle element and including a member having spaced parts each of which is formed for selective attachment to the arm, and also a spring for preventing 35 loose play between the member and arm in either position of the member.

3. An accelerator pedal consisting of detachably and pivotally connected sections 40 one of which is formed with a series of corrugations radiating from the pivotal connection, and an arcuate slot, and the other section formed to intermesh with said series, and means operable in the slot for securing the two sections relatively fixed.

4. An accelerator construction for motor vehicles, comprising a pedal, a rock shaft on which the pedal is fixed, an arm fixed on the shaft, a throttle member, and means connecting the arm to the throttle member and including a link having one end portion bent

upon itself in spaced relation to provide relatively superposed portions at said end for selective attachment to the arm.

5. An accelerator construction for motor vehicles, comprising a pedal, a rock shaft on 55 which the pedal is fixed, a rocker arm fixed on the shaft, a throttle member, a bracket plate secured between its ends and having one end formed to laterally engage beneath a clamping nut, a bell crank lever pivoted on 60 the opposite end of said bracket plate, means connecting the arms of said bell crank lever respectively to the rocker arm and a control member, a second rocker arm fixed on the shaft, and a resilient connection between the 65 outer end of said second rocker arm and the second end of said bracket plate tending to hold the opposite end of the latter operatively disposed.

6. An accelerator construction for motor 70 vehicles, comprising a pedal, a rock shaft on which the pedal is fixed, a rocker arm fixed on the shaft, a throttle member, a bracket support, a lever pivoted on the latter and having operative connection with the rocker 75 arm and a control member, a second rocker arm on said shaft overlying the bracket support, and a spring connected at one end to the latter and to the outer end of said second 80 rocker arm for adjustment lengthwise of the latter.

7. An accelerator construction for motor vehicles, comprising a pedal, a rock shaft on which the pedal is fixed, an arm fixed on the shaft, a throttle member, means connecting the arm to the throttle member and including a link having one end portion bent upon itself in spaced relation to provide relatively superposed portions at said end for selective attachment to the arm, a lever, and 85 means detachably connecting the lever to the opposite end of the link whereby the latter may be removed and inverted, and then reconnected to the arm and lever.

In testimony whereof I have affixed my 90 signature in the presence of two witnesses.

EDWARD H. ELLISON.
